UNITED STATES PATENT OFFICE

ISAIAH B. KIMMEL AND JOHN V. STEWART, OF JOHNSTOWN, PENNSYLVANIA

PARALLEL THROW SWITCH STAND

Application filed November 20, 1931. Serial No. 576,404.

This invention relates to switch stands and more particularly to switch stands of the parallel throw type.

One of the objects of the present invention is to provide an improved parallel throw switch stand device.

Another object of the present invention is to provide a simplified assembly of elements comprising a parallel throw switch stand.

10 Still another object of the present invention is to provide a parallel throw switch stand in which the elements thereof may be readily removed and replaced when desired.

Other objects and advantages will be apparent as the invention is more fully herein-after disclosed.

In accordance with the objects of the present invention we have devised a novel assembly of elements comprising a parallel throw switch stand including a housing, a vertically supported spindle therein, a throw lever and a thrust rod. Means are provided to translate the throw movement of the lever into a rotational movement of the spindle and 25 means are provided to translate the rotational movement of the spindle into a thrusting movement in the thrust rod, thereby actuating the switch mechanism. Means also is provided to indicate the position of the 30 switch mechanism.

Before further disclosing the nature and scope of the present invention reference should be made to the accompanying drawing in which—

35 Fig. 1 is a side elevation view of the parallel throw switch stand device of the present invention;

Fig. 2 is a view taken along plane 2—2, Fig. 1;

40 Fig. 3 is a horizontal section on line 3—3, Fig. 5;

Fig. 4 is a vertical section on line 4—4 of Fig. 3;

45 Fig. 5 is a vertical section on line 5—5 of Fig. 3;

Fig. 6 is a detailed perspective view of the spindle of the present invention;

Fig. 7 is a detailed perspective view of an adjustable lever member of the present invention;

Fig. 8 is a perspective view of a toggle member adapted for use in the present invention; and

Fig. 9 is a perspective view of the operating end of the throw lever of the present invention.

Referring to the drawings Fig. 1, the parallel throw switch stand of the present invention comprises a housing 1, a vertically supported spindle 14, a throw lever 5 and a thrust rod 24.

The housing 1 is preferably of one piece as shown and is provided with pads 2 adapted to be bolted to ties 3—3 by bolts 4 substantially as shown.

Spindle 14 is vertically supported within the housing 1 and is adapted to rotate about its longitudinal axis X—X by means of journal portions 15 and 16 adapted to engage in journal bearings 17 and 18 located in the top and bottom respectively of housing 1. Preferably spindle 14 is comprised of one piece as shown which may be a casting. Alternatively, however, the spindle may be assembled from a plurality of parts into a unitary piece.

To provide means to translate the throw movement of lever 5 into a rotational movement of spindle 14, lever 5 is provided with an extension arm 8 carrying a bearing recess 9 and spindle 14 is connected thereto by means of toggle member 11 carrying ears 12—12 adapted to be attached to spindle 14 by pin 13 substantially as shown. Toggle 11 also carries bearing extension 10 adapted to engage bearing recess 9 in extension 8 of lever 5.

When lever arm 5 carrying weight 31 is rotated about the pin bearing 6 to dotted position indicated at 32 extension arm 8 rotates

therewith and thus displaces toggle 11 causing thereby a rotation of spindle 14 in a counter-direction.

A 180° movement of the operating lever 5 will rock the toggle member 11 and the vertical spindle 14 through an angle of substantially 90° in a counter-direction.

To provide means to convert this rotary movement into a thrust motion we provide a hub 20 integral with spindle 14 said hub having a threaded bore 19. Threaded through the bore 19 of the hub 20 we provide a rod-like lever arm 21 having an eye 22 on one end thereof which is connected by a pin 23 to the thrust rod 24 which is adapted to be connected at 25 with a movable switch point 26 (Figs. 2 and 3). Threaded bolt 21 is adjustable with respect to the position of thrust rod 24. Upon a rotation of spindle 14 in either direction the rotational movement is thus converted into a thrust movement in rod 24.

To provide for ready assembly of the elements comprising the switch stand of the present invention casing 1 is provided with bearing openings 17 and 18 at the top and bottom respectively of the casing. Top opening 17 has a diameter which is sufficiently great to permit spindle 14 to pass therethrough. Opening 18 is of such a diameter as to receive the journal portion 16 of the spindle 14. Shoulder 36 Fig. 6 of the spindle 14 rests on the top of the bottom section of casing thus preventing the spindle from falling therethrough. Journal 15 is substantially of a diameter to substantially fit within the larger journal opening 17 in the top of casing 1.

Means are provided comprising a retaining collar 35 adapted to be attached to the protruding end of spindle journal 16 to prevent vertical displacement of the spindle 14. Supporting means 27 adapted to be attached to the top of the spindle 14 so as to rotate therewith is provided to carry the signal or lamp indicating means 36 as may be desired.

To provide signal indicating means spindle 14 carries said supporting means 27 upon the upper bearing 17 to attach thereto shaft means 28 adapted to carry the signal or lamp indicating means 36 in such manner that the same is rotatable therewith.

The assembly of elements comprising the switch stand of the present invention may be readily assembled, and readily taken apart, and the parts utilized therein may be replaced and interchanged. Due to the simplified structure the operation of the same is efficient and reliable.

From the above description and the drawings it is believed that modifications and departures may be made in the several elements comprising the parallel throw switch device of the present invention without departing essentially from the specific embodiment herein disclosed and such modifications and departures are anticipated as may fall within the scope of the following claims:

What we claim is:

1. In a switch stand of the parallel throw type, a one piece housing, a double bearing spindle vertically supported in said housing, a double bearing throw lever adapted to rotate said spindle, and a thrust rod adapted to be actuated by the rotation of said spindle to operate switch mechanism.

2. In a switch stand of the parallel throw type, a one piece housing and a spindle, and means to vertically support the spindle in said housing, said means comprising journal bearings oppositely positioned in the top and bottom of said housing and journal extensions spaced on said spindle to rest in said bearings, the top bearing having a diameter sufficient to permit the spindle and lower extension to be passed therethrough, and the bottom bearing having a diameter sufficient to receive said lower journal extension, collar offset means on said spindle adjacent the journal extension to support the spindle in said bearing, the opposite journal extension on said spindle being adapted to ride in the larger upper journal bearing of said housing, and thrust collar means adapted to engage the end of said journal extension protruding through the lower bearing to retain the spindle from vertical displacement.

3. In a switch stand of the parallel throw type comprising a one piece housing, a double bearing spindle vertically supported in said housing, a double bearing throw lever and a thrust rod adapted to operate switch mechanism, means to translate the throw movement of the lever into a rotational movement in said spindle, and means to translate the rotational movement of the spindle into a thrusting movement in said throw rod.

4. In a switch stand of the parallel throw type a one piece housing, aligned bearings in the top and bottom of said housing, a spindle vertically supported in said bearings, a double bearing throw lever and a thrust rod adapted to operate switch mechanism, means to translate the throw movement of the lever into a rotational movement in said spindle, and means to translate the rotational movement of the spindle into a thrusting movement in said throw rod, said throw movement translating means comprising a toggle member adapted at one end to engage a pin member passing through said spindle along a plane transverse to the longitudinal axis thereof and adapted at the opposite end to engage in a bearing recess of the said lever.

5. In a switch stand of the parallel throw type a one piece double bearing housing, a double bearing spindle supported therein, a double bearing throw lever and a thrust rod adapted to operate switch mechanism, means

- to translate the throw movement of the lever into a rotational movement in said spindle, and means to translate the rotational movement of the spindle into a thrusting movement in said throw rod, said rotational movement translating means comprising a threaded bolt member adapted to engage a threaded recess in said spindle, the head of said bolt being adapted to rotatably engage the end of said thrust rod. 10
6. In a switch of the parallel throw type a one piece housing, aligned bearings in the top and bottom of said housing, a double bearing spindle supported therein, a double bearing throw lever and a thrust rod adapted to operate switch mechanism, toggle means connecting said lever through one bearing to said spindle to translate the throw movement of said lever into a rotational movement in said spindle, and means to translate the rotational movement of said spindle into a thrust movement into said thrust rod. 15
7. A parallel throw switch stand comprising a one piece housing, aligned bearings in the top and bottom of said housing, a double bearing spindle supported therein, a double bearing throw lever, a thrust rod, and means to translate the throw movement of the lever into a rotational movement of the spindle and thence into a thrusting movement in said rod. 20
8. A parallel throw switch stand comprising a housing having aligned bearings in the top and bottom sections thereof, a double bearing spindle supported therein, a double bearing throw lever and a thrust rod adapted to move a switch mechanism, a toggle member adapted to engage the spindle and a bearing in the throw lever so as to translate the throw movement of the lever into a rotational movement of the spindle, and means to translate the rotational movement of the spindle into a thrusting movement in said rod. 25
- 45 9. A parallel throw switch stand comprising a one piece housing with aligned bearings in the top and bottom sections thereof, a double bearing spindle supported therein, a double bearing throw lever, a thrust rod, means to translate the throw movement of the lever into a rotational movement of the spindle and thence into a thrusting movement in said rod and means rotatable with the spindle to indicate the rotational position of the spindle. 50
10. A parallel throw switch stand comprising a one piece housing, a double bearing spindle vertically supported therein, a double bearing throw lever and a thrust rod adapted to move a switch mechanism, a toggle member adapted to engage the spindle and a bearing in the throw lever so as to translate the throw movement of the lever into a rotational movement of the spindle, and means to translate the rotational move- 55 60 65
- ment of the spindle into a thrusting movement in said rod and sign indicating means carried by the spindle to indicate the position of the switch mechanism. 70
- In witness whereof, we have hereunto signed our names. 75
